APPARATUS FOR DEHYDRATING OIL.

1,297,378.

Specification of Letters Patent. Patented Mar. 18, 1919.

Application filed October 2, 1916. Serial No. 123,244.

To all whom it may concern:

Be it known that we, FRED W. McNEAR and PHILIP E. BOWLES, Jr., citizens of the United States, residing, respectively, at 5 Menlo Park, in the county of San Mateo and State of California, and at Reward, in the county of Kern and State of California, have invented a certain new and useful Apparatus for Dehydrating Oil, of which the 10 following is a specification.

The invention relates to an apparatus for separating water from emulsified oils, particularly those which come from oil wells.

An object of the invention is to provide an 15 apparatus for efficiently separating water from emulsified oil.

Another object of the invention is to provide an apparatus which is adjustable for efficient operation on emulsions of different 20 percentages of water.

Another object of the invention is to provide an apparatus in which the separation is continuously and completely effected thus obviating the necessity of using settling 25 tanks for the water after treatment in the treatment tank.

The invention possesses other advantageous features, some of which, with the foregoing, will be set forth at length in the 30 following description where we shall outline in full that form of the apparatus which we have selected for illustration in the drawing accompanying and forming part of the present specification. In the drawing we have 35 shown one specific form of the apparatus of our invention, but it is to be understood that we do not limit ourselves to such form, since the apparatus may be embodied in a plurality of forms without departing from the invention as expressed in the succeeding 40 claims.

The drawing is a vertical section of the apparatus.

The apparatus comprises a metallic tank 45 2, closed at the bottom and open at the top. Arranged in the tank in superposed relation are a plurality of annular electrodes 3, the electrodes being formed so that they may be readily placed in or quickly removed from the 50 tank when desired. Secured to or formed integral with each annular disk is a shoulder 4 which contacts with the side of the tank and depending from each disk is an apron 5 which rests upon the disk or shoulder next 55 below, or upon the tank bottom, thereby sup-

porting the electrodes in position. The electrode units, comprising the disk, shoulder and apron are preferably of the same size, with the exception of the lower one, so that the electrodes are spaced apart evenly in the 60 tank.

Depending into the tank is a guide 6, upon which are mounted a plurality of circular disk electrodes 7, these circular electrodes being of opposite sign to the annular electrodes. The circular electrodes are preferably slightly larger in diameter than the aperture in the annular electrodes, so that the electrodes overlap somewhat and so that their edges are adjacent. The spacing 70 of the electrodes 4 and 7 preferably varies at different depths in the tank, those at the top being closer together than those at the bottom. The emulsion of oil and water is introduced into the tank 2 through the pipe 75 8 which discharges through the head 9, arranged centrally within the tank below the lowest annular electrode 3. The emulsion passes up through the tank, between the electrodes 3 and 7 where it is subjected to the 80 action of the electric current which separates the oil from the water. As the emulsion passes up through the tank, the percentage of oil therein increases, thereby increasing the electrical resistance of the emulsion. On account of this increasing resistance it is preferable to arrange the upwardly successive pairs of electrodes 3 and 7 closer 85 together. In order to maintain this effect and to accommodate emulsions of different 90 percentages of oil and water, the pairs of electrodes are movable with respect to each other, so that the distances between them may be varied and this is preferably accomplished by moving the circular electrodes 95 7 vertically. The electrodes 7 are slideable on the guide 6 and are supported by vertically adjustable rods 12 connected to the electrode hubs and passing through a stationary plate 13, the rods being threaded 100 and provided with nuts to accomplish the adjustment. By this means the lengths of one or all of the current paths through the emulsion may be varied.

The guide 6 and circular electrode supporting rods 12 are supported on a frame 14 preferably arranged within the tank and supported on insulators 15, which are fixed on brackets 16 secured to the tank. In order 105 to permit the insertion or withdrawal of the 110

annular electrode units from the tank, the upper portion 17 thereof is of increased diameter, so that the distance between the insulators is greater than the diameter of the 5 annular electrode units. The oil from which the water has been separated flows from the tank through the pipe 18, which is preferably arranged at such a point that the insulators are immersed in the oil in the 10 tank, the oil being a very efficient insulator. The water which has been separated from the emulsion discharges through the pipe 19 which extends upward to such height that the column of water therein balances the 15 column of emulsion in the tank. The pipe 21, through which the water discharges, is turned up or down to adjust the height of the column of water in pipe 19 to maintain the level in the tank at the desired point.

20 Alternating current from the power mains 23 is passed through the primary of a step up transformer 24 to raise it to the necessary potential and an inductive reactance 25 is placed in series, with said primary, for the 25 purpose of limiting the amount of current which may be drawn from the power mains. One side of the secondary of the transformer is connected to the circular electrodes and the other side is grounded and the tank is 30 also grounded.

We claim:

1. In an apparatus of the character described, a tank having a conducting inner surface, a plurality of axially spaced annular electrodes in said tank connected to one side of a source of potential and electrically connected to said conducting surface, and a plurality of disk electrodes connected to the other side of the source of potential 35 and arranged between and spaced axially from the successive annular electrodes, the spaces between the annular electrodes being otherwise clear to permit the free flow of liquid through the successive annular electrodes and around the successive disks.

2. In an apparatus of the character described, a tank having a conducting inner surface, a plurality of axially spaced electrodes in said tank forming tight joints 50 with said inner surface, whereby liquid passing through said tank must pass through the apertures in said electrodes, said electrodes being connected to one side of a source of potential, and a plurality of disk electrodes connected to the other side of the source of potential and arranged between and spaced axially from the annular electrodes, whereby liquid passing through the tank flows past the inner edges of the 55 annular electrodes and the outer edges of the disk electrodes.

3. In an apparatus of the character described, a tank having a conducting inner surface, a plurality of axially spaced annular electrodes in said tank forming tight 65

joints with said inner surface and electrically connected to said inner surface and to one side of a source of potential, and a plurality of disk electrodes connected to the other side of the source of potential and arranged between and spaced axially from the annular electrodes whereby liquid passing through the tank flows in a tortuous path past the inner edges of the annular electrodes and the outer edges of the disk electrodes, the distance between the outer edge of a disk electrode and the inner edge of the adjacent annular electrodes being equal at all points on said edges. 70

4. In an apparatus of the character described, a tank having a conducting inner surface, a plurality of annular electrodes in said tank forming tight joints with and being electrically connected to said inner surface, said electrodes being otherwise imperforate, said annular electrodes being electrically connected to one side of a source of potential, and a plurality of imperforate disk electrodes of lesser diameter than the annular electrodes arranged between and spaced axially from the annular electrodes and connected to the opposite side of said source of potential; whereby electrostatic fields are set up between the disks and the annular electrodes and inner surface, the electrodes being arranged so that the electromagnetic field is strongest between the outer edge of a disk and the inner edge of an adjacent annulus. 85

5. In an apparatus of the character described, a tank, a plurality of electrodes of opposite sign arranged alternately and spaced apart vertically in said tank, the distances between the alternate electrodes decreasing upwardly. 100

6. In an apparatus of the character described, a tank, a plurality of annular electrodes spaced apart vertically in said tank and a plurality of circular electrodes arranged intermediately between said annular electrodes, the distances between the alternate electrodes decreasing upwardly. 110

7. In an apparatus of the character described, a tank, spaced electrodes of opposite sign arranged in said tank and lying closer together at the top of the tank than at the bottom. 115

8. In an apparatus of the character described, a tank having a conducting inner surface, a plurality of imperforate annular electrodes in said tank forming tight joints with and being electrically connected to said inner surface, a rod supported at its upper end and depending in said tank, a plurality of imperforate disk electrodes arranged on 120 said rod and disposed between and spaced from said annular electrodes and means connecting the disk and annular electrodes to opposite sides of a source of potential. 125

9. In an apparatus of the character de- 130

scribed, a tank, a plurality of electrodes arranged in said tank, a plurality of electrodes of opposite sign suspended in said tank, a frame on which said suspended electrodes are suspended, and insulators arranged within the tank and adapted to be immersed in the oil therein, supporting said frame.

10. In an apparatus of the character described, a tank, a plurality of annular electrodes spaced apart vertically in said tank, electrodes of opposite sign arranged between the annular electrodes and a centrally arranged inlet pipe discharging below the 15 lower annular electrode.

11. An apparatus for treating petroleum emulsion to separate the oil and the water, comprising a tank, means in the tank for separating the oil and water, an emulsion inlet pipe arranged in the bottom of the tank 20 below said means, an oil discharge pipe arranged at the top of the tank above said means and a water discharge pipe arranged at the bottom of the tank below the discharge end of the emulsion inlet pipe. 25

In testimony whereof we have hereunto set out hands.

FRED W. McNEAR.
PHILIP E. BOWLES, JR.
